(57) **CLAIM**

The ornamental design for a neck and backbone traction apparatus, as shown and described.

DESCRIPTION

FIG. 1 is a top and front perspective view of a neck and backbone traction apparatus, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference perspective view showing how the neck and backbone traction apparatus can be coupled with an article;

FIG. 9 is a reference perspective view in an alternate position thereof showing how the neck and backbone traction apparatus can be coupled with other articles;

FIG. 10 is a reference perspective view showing how the neck and backbone traction apparatus can be used in an application thereof; and,

FIG. 11 is a reference perspective view showing how the neck and backbone traction apparatus can be used in another application thereof.

The broken lines in the form of two air bags, a head strap, and a human upper body shown in FIGS. 8-11 depict environmental subject matter and form no part of the claimed design.
